VOICE INFLECTION DETECTION CIRCUIT
Genung L. Clapper, Vestal, N.Y., assignor to International
Business Machines Corporation, New York, N.Y., a
corporation of New York

Filed Dec. 29, 1961, Ser. No. 163,327
7 Claims. (Cl. 179—1)

The present invention relates to an inflection detection apparatus and in particular to an inflection detection apparatus particularly designed to detect inflections in speech.

In relation to speech, the voiced sounds are generated by the vocal chords as air from the lungs is passed through the same. The waveform of the sound generated at the vocal chords is a sawtooth which it is recognized contains all frequencies when analyzed into Fourier components. This sawtooth waveform is not however transmitted as sound external to the speaker but is resonated by cavities formed by the mouth, tongue, and lips so that the externally generated sound will be those frequencies contained in the sawtooth which are acoustically resonant with the sounding box formed by the mouth, tongue, teeth, and lips.

The frequency of the sawtooth is the fundamental pitch. Most men use a pitch in the lower part of their vocal ranges, typically from 110 to 140 cycles per second. Women and children also use the lower part of their vocal ranges, which is an octave higher than men. The range in fundamental pitch in speech is usually small for a given speaker, but inflections occur which may carry more information than the actual pitch.

For example, consider the following illustrations of inflection as a key to the intelligence contained in a word.

"one" -----	R-F-S	R -----	rising voice
"seven" -----	S-R-F	S -----	steady voice
"eight" -----	R-F-R	F -----	falling voice
"nine" -----	R-S-F		

While the illustrative embodiment is applied particularly to speech or sound, it should be understood that the invention could as well be used in detecting inflection in any form of complex wave.

In general the inventive concept of the present invention involves a detecting circuit for the fundamental frequency contained in the waveform being analyzed and a balanced integrator having an output which is the same for no input as for a median frequency input wherein no time is wasted or erroneous indications generated while the modulator goes from no input to a median frequency input.

It is therefore an object of the present invention to provide apparatus for detecting inflection.

It is a further object of the present invention to provide apparatus for detecting inflection in a complex wave.

Another object of the present invention is to provide apparatus for detecting inflection in speech.

Still another object of the present invention is to provide apparatus for detecting the fundamental frequency of the intelligence medium being monitored.

Yet another object of the present invention is to provide apparatus for monitoring frequency and providing the same output when the input is zero or at a median frequency.

Another and further object of the present invention is to provide apparatus for monitoring speech, detecting the fundamental frequency of the sawtooth waveform contained therein, and generating an output indicative of inflection wherein the absence of a fundamental frequency and the presence of a median frequency fundamental provide the same output.

The foregoing and other objects, features and advantages of the invention will be apparent from the following

2

more particular description of a preferred embodiment of the invention, as illustrated in the accompanying drawings.

In the drawings:

FIG. 1, consisting of FIGS. 1a, 1b, and 1c, is a circuit diagram of the invention.

FIG. 2 is a chart of the waveforms concerned with the balanced modulator circuit 94 of FIG. 1b.

FIG. 3 is a chart of the inflection detection logic circuit of FIG. 1c.

FIG. 4 is a chart illustrating how FIGS. 1a-1c are to be arranged to form FIG. 1.

In general, FIG. 1a discloses a preamplifier responsive to voice frequencies for providing at 29 a signal of a uniform amplitude. In the process of generating a uniform envelope output signal, a feedback circuit is provided. An output 47 will have a signal contained thereon indicative of the variations in magnitude of the input speech frequencies. Since speech contains a sawtooth amplitude variation at the fundamental frequency of the voice, there will be amplitude variations in the input signal. Thus signals on line 47 will be at the fundamental frequency of the voice. While speech is the input signal used here, it should be understood that any signal can be monitored, and the fundamental extracted with this inventive concept. Suitable modifications would of course be made for the range of frequencies being monitored.

The fundamental frequency signal on line 47 is shaped by a pulse shaping circuit 86, FIG. 1b, and applied to a balanced integrator 94. An output voltage on output 127 is developed indicating a normal or median fundamental or a rising or falling fundamental.

This output 127 is applied to a voltage change detector and logic circuit, FIG. 1c, wherein an output at 165 and/or at 171 is developed indicative of inflection.

35 This invention forms a part of the invention disclosed in application Serial No. 161,089 to Genung L. Clapper. The preamplifier, FIG. 1c, is further disclosed and claimed in application Serial No. 161,088 to Genung L. Clapper.

In the compression of speech and audio waveforms, 40 there are generally several requirements involved. One of these is that the compression attack be as fast as possible without too much overshoot, and the other is that the response after compression be fast to enable the indication of the weaker speech sounds. Also a definite level of 45 over-all sensitivity must be established to prevent noise amplification in periods of silence. This is often not done in regular public address equipment, the compression usually being rather slow which tends to average out the volume, and it is possible to have considerable delays 50 both in the attack and recovery without serious problems. However, in speech analysis equipment there is needed both a fast attack and recovery, and furthermore it is desired that no appreciable distortion be introduced since a frequency analysis is made of the speech waveform and 55 any clipping or other distortion would introduce frequencies which would upset any frequency analysis or speech recognition code that might be used. Former methods of compression have utilized a gain control operating upon the first or second stages of a preamplifier. Although this 60 method is efficient, the operation is usually somewhat slow because of unavoidable delays produced by the relatively long time constants of the coupling networks.

Referring to FIG. 1a, a dynamic microphone 10 is shown feeding through input capacitors 15 to a preamplifier circuit which comprises two transistors 17 and 19. These stages are conventional capacitor-coupled grounded emitter stages operating in class A amplification with a high degree of degenerative feed-back in each stage. Input sensitivity is controlled by changing the gain 65 of transistor 17 through a change in its operating point by means of a manually controlled potentiometer 13.

A preamplifier output at the collector of transistor 19

is reflected through capacitors 21 to the base of a transistor 23. Transistor 23, along with a transistor 25, cooperates to form a voltage amplifier having inherent compression properties. Transistor 23 operates to control the current flowing in the emitter of transistor 25 and transistor 25 operates as a grounded base voltage amplifier.

The signal appearing at the base of transistor 23 is A.C. and the swing in the range of tenths of a volt. In the no-signal condition, both transistors 23 and 25 are biased at approximately the same voltage, and equal currents will flow in both. When conductivity is decreased or increased in transistor 23 by virtue of the A.C. signal, the change in current flow through transistor 23 will effect the transistor 25 in the inverse manner since these transistors form a parallel circuit.

The voltage at the collector of 25 will vary in the same manner as the input signal at the base of transistor 23. A resistor 33 having a value of 2,000 ohms has connected in parallel thereto a capacitor 49 for reflecting these A.C. voltage changes to a circuit 51.

Also connected by capacitors 31 to the collector transistor 23 is a network of A.C. signal sensing transistors 39, 45, and 43. Transistors 39 and 43 are connected by diodes 37 and 41 to the capacitors 31, and these transistors are normally biased near conduction when no A.C. signal is applied across capacitors 31.

When a positive change is sensed at the collector of transistor 25, the diode 37 couples the same to transistor 39 and causes conduction. When transistor 39 conducts, the collector drops toward ground potential, and the transistor 45, normally biased off, conducts and raises the potential at its collector.

In a similar manner, negative changes at the collector of transistor 25 cause conduction in transistor 43 which also generates a positive voltage signal at its output.

These positive pulses from transistors 43 and 45 indicative of positive and negative swings of voltage at the collector of transistor 25 are coupled to an integrator circuit 61, 59, 63, and 65. As these positive pulses cause conduction in transistor 61 and establish a given voltage at the collector thereof, the capacitor 63 will, by contributing and accepting current at the base, tend to keep the transistor 61 at a steady conducting stage so that peaks of voltage from transistors 43 and 45 will not affect the operation. This is a Miller type integrator.

An incandescent lamp 59 connected to the collector of transistor 61 acts as a resistance integrator in that pulses of random nature which may cause conduction in transistor 61 will not cause a voltage drop across lamp 59, and thus the voltage at the collector of transistor 61 will stay at ground potential.

When the signal at the collector of transistor 25 increases in amplitude other than for short peaks, the voltage at the collector of transistor 61 will drop to some value less than ground potential.

A bilateral transistor 53, i.e., having two emitters, is normally maintained in a given state of conductivity by the potential applied to the base thereof by the lamp 59. When there is no integrating action of integrator 61 and the base is at ground potential, transistor 53 is nonconducting and thus presents a high impedance to any signal applied to capacitor 49. Thus for a no-change signal condition at the base of collector 25, the circuit 51 is a high impedance.

For signal conditions which vary positively and cause integration by the integrator 61, the transistor 53 is biased more conducting. The increased current through transistor 25 sees a lower impedance through capacitor 49 which prevents the voltage at collector 25 from rising. In this the emitter of transistor 53 which is used is 57.

For negative type signal excursions the same result occurs, but here the emitter is 55, and the circuit 51 transfers current through capacitor 49 to raise the voltage output.

The output of transistor 61 is the AGC voltage and

governs the conduction of a bilateral transistor 53 which reflects an impedance to the preamplifier output stage 25 which is an inverse function of the AGC voltage. The preamplifier gain of the transistor 25 is variable as a function of the load. Therefore, by changing the effective impedance of the amplifier 25, the output gain of the transistor 25 may be varied, and the input speech frequency may be compressed into the uniform envelope.

Increased compression voltage results in increased conduction and lower impedance which lowers the gain of the last stage 25 so controlling the output amplitude without excessive distortion. The result is to speed up the compression action without introducing oscillations or distortion. Thus a relatively constant amplitude signal appears at the base of a PNP transistor 25 which drives an output stage 27.

As the pressure time pattern of the sawtooth waveform varies from a maximum to a minimum, the amplitude of the output speech envelope will also vary in amplitude from a maximum to a minimum. While this pattern of rising and falling is not readily apparent when varying the waveform at the collector of transistor 25, the amplitude detecting transistors 43 and 45 will provide an output pulse at low and high levels. These pulses are used as previously explained to bias the transistor 53 to the proper conductive state to generate a uniform output envelope at the output at the collector of transistor 25. Thus while it may appear paradoxical at first, it is also apparent that the bias on transistor 53 must be kept at the proper level by variations in the input which the circuit 53 is to control. These are of course small variations which are detected by transistors 43 and 39 and are merely sufficient to keep transistor 53 properly biased.

Thus while transistor 39 is responsive to the positive peaks of amplitude of the generated speech, the output has been taken from the negative amplitude detecting circuit 43. This is a practical arrangement since the microphone produces a more negative voltage for increased sound pressure, and the preamplifier has an even number of stages and therefore causes no inversion.

The output of transistor 25, FIG. 1a, is supplied to a transistor 27 which supplies an output 29 at its emitter. The envelope of speech frequencies is supplied to an amplifier 67, FIG. 1b, which is responsive only to the low frequencies of the voice and then to an integrating shaper 69 which generates a raised output in response to these low frequencies. The output from shaper 69 is used as will be described subsequently as an interlock to prevent an output in the absence of voice. The details of this circuit will be found in application Serial No. 161,089 to Genung L. Clapper.

The pulses at the fundamental frequency at output 47 are coupled through a diode 71, FIG. 1b, to an integrating network consisting of resistor 73 and capacitor 81. The positive-going pulses on line 47 charge the capacitor 81 and start conduction in transistor 77. The transistor 77, when starting into conduction, supplies current to one side of the capacitor 81. This acts as a smoothing type of integrating device for the incoming square waves which may be quite ragged because of the high frequency content of the input signal. Small negative excursions, etc., on the positive-going waveforms on line 47 will be resisted by the capacitor 81 which is being held up by the current action of the transistor 77 on the opposite plate of the capacitor.

The resulting square wave suitably smoothed appears at the collector of the transistor 77 and is applied to the base of a transistor 83. When the potential at the collector of transistor 77 reaches a value sufficiently negative, the transistor 83 will be biased into conduction to supply a positive-going pulse through diode 85 to the output line 87, line B, FIG. 2. This positive-going pulse is reflected back through capacitor 84 to reinforce the conduction of transistor 77 so that now both transistors 77 and 83 are conducting.

The potentiometer 79 can vary the time in which it takes the positive charge produced on the capacitor 81 to decay. This allows a differentiation to be made for masculine and feminine speakers since it is possible that the feminine speaker might produce positive-going pulses on line 47 with a frequency too high to allow capacitor 81 to discharge. When the capacitor 81 has discharged sufficiently from the pulse on line 47, the potential at the collector of transistor 77 will drop and bias off the transistor 83. The diode 85, through which the pulse is transferred into the line 87, was utilized to bias the transistor 89 to an off condition. Ordinarily when the transistor 83 is off, the transistor 89 is biased to conduction by the -12 volts to the base. Therefore, when the transistor 83 is cut off and the line 87 drops to the -12 volts, a sharp negative excursion is reflected back through the capacitor 84 to insure cutoff of transistor 77. The circuit 86 therefore has reached a stable condition and is ready for the next positive-going pulse on line 47.

The output 87, line B, FIG. 2, is applied to a balanced integrator 94 from which is derived a voltage proportional to the frequency of the digital pulse input. This integrator is a novel circuit and differs from known former integrators in that the voltage output for no input is the same as that for a median frequency input. Thus a change from no signal to the median frequency produces no change in the output. This allows an input to be intermittent with a minimum of delay incurred at the beginning of each group of pulses.

The great advantage in using this type of integrator is that no recovery time is lost in going from a no-signal condition to a normal condition. In addition the characteristics of the circuit insure fast response and short as possible recovery time from abnormal conditions. Any changes in frequencies is promptly reflected in the change of output voltage.

If there are no pulses present on line 87, capacitors 91 and 93 isolate the output 87 from D.C. voltages so that the points 95 and 99 will not be affected by D.C. conditions. Point 99 will be very near ground potential or zero volts by virtue of the diode 103 and point 95 very near the negative potential -12 volts by reason of the clamp diode 117. With point 99 at zero volts and point 95 at -12 volts, no cutoff bias can be supplied to either transistor since the PNP transistor 107 needs a voltage more positive than zero, and the NPN transistor 115 needs a voltage more negative than -12 volts. Both transistors therefore will conduct and base current flows as follows: From ground 105 to the emitter of transistor 107 to the emitter base junction to the base of 107 through the resistors 111 and 113 to the base of transistor 115 through the emitter base diode of the transistor 115 to -12 volts. Transistor current will therefore flow from ground 105, transistor 107, resistor 125, resistor 121, transistor 115 to -12 volts. Current flowing in this circuit holds the output voltage at output 127 to -6 volts since both transistors will be saturated, and there will be little voltage drop across either one.

The transistor 115 and capacitor 119 combination, as well as the transistor 107 and capacitor 109 combination, are Miller integrators. A Miller integrator is essentially an integrator having an amplifier connected to the output, and a degenerative feedback from the output of the amplifier to the output of the integrator to insure stability of operation.

In the pulse input to the integrators 101 and 109, the negative level of the input pulses, FIG. 2, will cause conduction in transistor 107 of a predetermined amount which will be resisted by the positive-going output pulses at the collector of transistor 107 reflected across the capacitor. By the same token, the positive rise at the base of 107 will be retarded by the collector current in the opposite phase. Thus the voltage at the collector will tend to remain constant for pulses having approximately 50% duration. As the pulses increase in negative dura-

tion, the transistor 107 will approach more closely to full conduction, and ground potential will be present at the collector.

At the same time that this is happening, the integrator 97 and integrator 119 with transistor 115 works inversely, and transistor 115 will gradually cut off. Potential at output 127 will then approach ground.

For pulses which have a longer positive duration, the inverse of the above will occur, and line 127 will approach -12 volts.

While the Miller integrator is well known in vacuum tube technology and the circuitry just described is substantially the entire circuit, it should be appreciated that the use of two transistors in a complementary configuration introduces an additional factor. This is the amplification factor which is very large in transistors and would in essence operate to move the output very rapidly to one extreme of output voltage or the other dependent on the positive or negative duration of the input pulses.

In order to prevent this event, the output 127 is fed back degeneratively by means of resistors 123, 111, and 113 to the inputs of the transistor 107 and transistor 115. These input resistors allow the output to assume an output voltage that continuously provides information as to the input pulse rate.

FIG. 2 illustrates the input waveforms and resulting output voltages.

The pulse chart of FIG. 2 shows the balanced integrator 94 with a number of different pulse conditions. For example, the normal input condition with input pulses having a period P1, the pulses, line A, are those which appear on line 47 indicative of the fundamental frequency of the sawtooth waveform used by the speaker. The pulses, line B, are the integrated pulses which appear on the output line 87 of the integrating circuit. Pulses are shown on the lines C and D, which are the voltages which appear at the point 99 and point 95, respectively, of the balanced integrator. These waveforms, lines C and D, have been labeled biased condition and conducting condition so that during the period labeled cond. the transistor 107 connected to point 99, which is affected by the pulses shown on line C, will conduct when the pulse waveform is in a down condition with the -1 voltage. On the up portion of the pulse, line C, the transistor 107 will be biased off.

The waveform, line D, which is applied at point 95, causes the opposite results. The transistor 115, which is the NPN type, is cut off when transistor 107 is conducting and vice versa.

A change in frequency to a lower frequency of period P2 results in a 40% bias condition for the PNP transistor 107 and a 60% conduction period while conversely the NPN transistor will now have 60% for bias and 40% for conduction. Under these circumstances, line E, which is the output 127 of FIG. 1b, will rise to -4 volts. For a higher frequency of period P3, the transistor 107 will conduct only 20% of the period while the transistor 115 will conduct 80% of the time, and the voltage at the line 127 will drop to -10 volts.

FIG. 3, in part, shows similar waveforms to that shown in FIG. 2. The output 47 shown in the first column is indicative of the pulse input, line A, of FIG. 2. The output 127 is the output from the balanced integrator 94 and shows that for no-voice condition or steady-voice condition the output is the same. On a rising-voice condition, the output 127 drops as indicated in FIG. 2 to voltages approaching -12 volts. A falling voice wherein the pulse period P1 is more extended in time will provide an output 127 which rises similar to that shown for period P2 in FIG. 2. The remainder of the chart will be explained subsequent to the description of the inflection detection circuit logic.

The output 127 of the balanced integrator is applied to an input clamp 131 which is rendered conducting by an input 129 to the base from the shapes 69, FIG. 1b,

which provides -12 volts to the base and keeps the line 127 at -6 volts, regardless of the integrator action during the no-voice periods. When voice is present, the clamp 131 is off, and the output on 127 is applied to a low pass filter 133. Under the steady-voice condition or no-voice condition, the input will be at or near -6 volts. Under these conditions, the transistor 135 for the low pass filter which consists essentially of the capacitor resistance network 133 and transistor 135 will reject jitter noise on the line 127 and pass only the low frequencies and provide an output 137 at approximately -6 volts.

With line 137 in a steady state condition, no changes will be reflected across capacitor 141 or capacitor 139, FIG. 1c. Under these conditions, the transistor 143, having a diode 145 connected from the base to the emitter, will not conduct, and the PNP transistor 147 will conduct and provide a raised voltage output on line 159. The NPN transistor 149 will be biased to conduction by the connection from ground through resistor 153 to the base, and the emitter, biased at -12 volts, will provide a negative signal at the collector of transistor 149 and cause conduction in transistor 155 and therefore cause the line 157 to be in a raised voltage condition. Therefore under no-voice or steady-voice condition, both lines 159 and 157 will be up and conditioning the AND circuits 161 and 167.

A negative change on line 127, FIG. 1b, which it will be remembered is a rising inflection, will be coupled to the line 137, and this negative change will cut off the transistor 149 and this in turn cuts off transistor 155 and causes the line 157 to drop to a low voltage output which is applied to the AND circuit 167. The negative voltage swing at emitter of transistor 143 will be clamped by the current flowing in the diode 145 connected to ground.

By the same token, a positive change on the line 137 indicating a falling inflection will be coupled through the capacitors 139 and 141 and cause conduction in the transistor 143, resulting in nonconduction of the transistor 147 to cause the line 159 to drop. This signal is applied to AND circuit 161.

Summarizing, the lines 159 and 157 are usually up and one or the other drops out for a rising inflection or for a falling inflection. These outputs are applied to the AND circuits 161 and 167 in conjunction with an input 129 from the voice circuit and AND circuits 161 and 167 will not be enabled until there is voice. When both inputs to the AND circuits 161 and 167 are up, the transistor 163 or transistor 169 is conditioned to conduct, and an appropriate output is provided on line 165 or line 171.

As indicated previously, the output on line 127, FIG. 1b, is the same for a steady voice at median frequency or for no voice input. It will be remembered that the transistor 131 is conditioned by line 129, indicating the presence of a voice. Therefore, if no voice is present, the lines 159 and 157 are up as indicated for no voice or steady voice and connected to the AND circuits 161 and 167. It will be remembered under the no-voice condition however that the line 129 will be down, and the AND gates will not be enabled so that under no-voice condition the lines 165 and 171 will be down. Under the steady-voice condition, the line 129 will be up, and the AND circuits 161 and 167 will be enabled and both lines 165 and 171 will be up for an indication of steady voice. For the conditions of rising voice and falling voice, FIG. 3 shows clearly the outputs which will be present on lines 165 and 171 under each of these conditions.

While the invention has been particularly shown and described with reference to a preferred embodiment thereof, it will be understood by those skilled in the art that the foregoing and other changes in form and details may be made therein without departing from the spirit and scope of the invention.

What is claimed is:

1. An inflection detection system for the fundamental frequency contained in a complex wave comprising:
  - (a) amplifier means responsive to said complex wave for generating an output signal;
  - (b) amplitude detecting means responsive to variations in the output of said amplifier for generating an output signal pulse;
  - (c) an integrating network responsive to pulses from said amplitude detecting means for applying a corrective signal to said amplifier to vary the amplification of the same to insure a uniform intensity output signal;
  - (d) an integrating pulse shaper connected to said amplitude detecting means and responsive to pulses therefrom to generate an output pulse having a predetermined duration;
  - (e) a balanced integrator connected to said integrating pulse shaper and responsive to said output pulses for generating an output voltage indicative of the frequency of the output pulses from said amplitude detecting means; and
  - (f) an inflection circuit responsive to said output voltage of said balanced integrator for generating an indication of variation in frequency from a median frequency.
2. The apparatus of claim 1 wherein said balanced integrator includes:
  - (a) a first signal responsive device;
  - (b) means for D.C. biasing said device to conduction wherein a low impedance path is provided, said bias means being so proportioned as to cause conduction in said first signal responsive device on one excursion of an input pulse and to be cut off on the other excursion;
  - (c) an input circuit connected to said integrating pulse shaper;
  - (d) means for isolating said first signal responsive device from D.C. signals present at said input circuit;
  - (e) an integrating circuit connected to said first signal responsive device for establishing a voltage proportional to the frequency of said pulses from said integrating pulse shaper;
  - (f) a second signal responsive device;
  - (g) means for D.C. biasing said device to conduction wherein a low impedance path is provided, said bias means being so proportioned as to cause conduction in said second signal responsive device on one excursion of an input pulse and to be cut off on the other excursion;
  - (h) means for isolating said second signal responsive device from D.C. signals present at said input circuit;
  - (i) an integrating circuit connected to said second signal responsive device for establishing a voltage proportional to the frequency of said pulses from said integrating pulse shaper;
  - (j) means for connecting said first and second signal responsive devices in series relation; and
  - (k) means for establishing an output circuit at the connection to said two devices.
3. The apparatus of claim 2 wherein said inflection circuit includes:
  - (a) a first voltage responsive device biased to nonconduction and responsive to positive increments of voltage to become conducting; and
  - (b) a second voltage responsive device biased to conduction and responsive to negative increments of voltage to become non-conducting, wherein the change in output signal of each of said devices is indicative of the fundamental frequency change at that time.
4. A balanced integrator operative to provide a D.C. output signal indicative of an input frequency including:
  - (a) a first signal responsive device;
  - (b) means for D.C. biasing said device to conduction

- wherein a low impedance path is provided, said bias means being so proportioned as to cause conduction in said first signal responsive device on one excursion of an input pulse and to be cut off on the other excursion;
- (c) an input circuit to said balanced integrator;
- (d) means for isolating said first signal responsive device from D.C. signals present at said input circuit;
- (e) an integrating circuit connected to said first signal responsive device for establishing a voltage proportional to the frequency of pulses at said input circuit;
- (f) a second signal responsive device;
- (g) means for D.C. biasing said device to conduction wherein a low impedance path is provided, said bias means being so proportioned as to cause conduction in said second signal responsive device on one excursion of an input pulse and to be cut off on the other excursion;
- (h) means for isolating said second signal responsive device from D.C. signals present at said input circuit;
- (i) an integrating circuit connected to said second signal responsive device for establishing a voltage proportional to the frequency of pulses at said input circuit;
- (j) means for connecting said first and second signal responsive devices in series relation; and
- (k) means for establishing an output circuit at the connection to said two devices whereby the output signal for no input signal is the same as a median frequency input signal.
5. The apparatus of claim 4 further including:
- (a) a first voltage divider network connected from said output circuit to the input of said first voltage responsive device; and
- (b) a second voltage divider network connected from said output circuit to the input circuit of said second voltage responsive device whereby operation of said voltage responsive device will be stabilized.
6. An inflection detection system for the detection of changes in the fundamental frequency of the voice including:
- (a) an amplifier for receiving said complex wave and providing an output signal of uniform intensity;
- (b) said amplifier including a feedback circuit to in-

sure uniform intensity in the output signal of said amplifier;

- (c) amplitude detecting means in said feedback circuit operative to generate an output signal in response to variations in intensity of said complex wave wherein the output signal is indicative of the fundamental frequency in said complex waveform;
- (d) an integrating pulse shaper connected to said amplitude detecting means and responsive to pulses therefrom to generate an output pulse having a predetermined duration;
- (e) a balanced integrator connected to the output of said integrating pulse shaper and responsive to said pulses for generating an output voltage indicative of the frequency of output signal from said amplitude detecting means;
- (f) a clamp connected to the output circuit of said balanced integrator and responsive to the absence of the voice band in said speech for nullifying the output voltage of said integrator; and
- (g) an inflection circuit responsive to said output voltage of said balanced integrator for generating an indication of variation in frequency from a median frequency.
7. The apparatus of claim 6 wherein said inflection circuit includes:
- (a) a first voltage responsive device biased to nonconduction and responsive to positive increments of voltage to become conducting; and
- (b) a second voltage responsive device biased to conduction and responsive to negative increments of voltage to become non-conducting, wherein the change in output signal of each of said devices is indicative of the fundamental frequency change at that time.
